UNITED STATES PATENT OFFICE.

RUFUS FREDERICK LEARNED, OF NATCHEZ, MISSISSIPPI.

ICE-MAKING MACHINE.

SPECIFICATION forming part of Letters Patent No. 714,494, dated November 25, 1902.

Application filed January 3, 1902. Serial No. 88,296. (No model.)

To all whom it may concern:

Be it known that I, RUFUS FREDERICK LEARNED, a citizen of the United States, and a resident of Natchez, in the county of Adams 5 and State of Mississippi, have invented new and useful Improvements in Ice-Making Machines, of which the following is a full, clear, and exact description.

My invention relates to improvements in 10 ice-making machines, and more particularly to the freezing-can that is adapted to receive the water which it is desired to freeze into a block of ice, said can being intended to receive from below a supply of compressed air 15 or gas, a portion or all of which is allowed to pass through the body of water and result in a clear transparent block of ice.

Among other things my invention has for 20 its object the provision of an improved can with a subchamber adapted to receive a charge of air or gas; to provide an improved valve mechanism adapted to close from liquid-pressure from above and below in order to exclude brine from entering the can and to 25 retain the fresh water in the can, said valve mechanism also to open freely to air or gas pressure from below; to provide means which effectually excludes any ammonia-gas or other vapor or odor present in the brine from entering 30 the can and contaminating the fresh water therein, and to prevent the brine from entering the air or gas supply pipe when the can is removed.

With these ends in view the invention consists 35 in the novel combination of devices and the construction and arrangement of parts, which will be hereinafter described and claimed.

Reference is to be had to the accompanying 40 drawings, forming a part of this specification, in which similar characters of reference indicate corresponding parts in all the figures.

Figure 1 is a side elevation of a freezing-can, partly broken away and showing certain 45 parts of my invention in section. Fig. 2 is an enlarged vertical sectional elevation through one of the embodiments of the parts comprising my invention. Fig. 3 is another sectional elevation of another embodiment of the parts 50 of my invention.

A designates a freezing-can which in many respects is similar to the cans employed in

ice-making apparatus of the can system. As herein shown, said can A is adapted to be suspended in the usual manner by the rim a, attached to the upper part of the can, resting on the bars b of the framework over the freezing-tank. The method of suspension is not material.

The bottom 5 of the can is not secured at 60 the extreme lower end of the can-body, but is recessed upward some distance from the extreme lower end, as shown in Fig. 1. This bottom is fastened to the can in any suitable way to form a water-tight joint, and the described arrangement of the bottom forms a 65 lower chamber 6 in the bottom end of the can. Said chamber is open from below and may fill with brine as the can is lowered in the freezing-tank until the brine is displaced by the 70 air or gas, which is admitted from below. To counteract the buoyant effect of the chamber filled with air or gas at the bottom end of the can, I attach an iron band as a rim to the lower part of the body of the can, as shown 75 by 7 in Fig. 1. This weighting may be accomplished in any suitable way.

I will first proceed to describe the construction embodying my invention as illustrated in Figs. 1 and 2, to which reference is now 80 more particularly made.

A flanged coupling-plate 8 is attached to the under side of the bottom of the can, preferably at the center and within the chamber 6 and is attached by rivets or in any suitable 85 manner. A nipple 9 forms an integral part of this coupling-plate, and said nipple is provided with an interior bore or passage, the latter having a female screw-thread. The bottom 5 of the can has an aperture, which is 90 made concentric with the bore of the nipple of the coupling-plate, and into this aperture and bore of the coupling-plate is fitted a valve cage or shell 10. The upper part of this valve-cage is fitted with a male thread adapted to 95 be screwed into the coupling-plate and aperture in the bottom of the can, as shown in Fig. 2; but it is evident that the valve-cage may be attached in any suitable manner. The valve-cage is provided at a point intermediate 100 of its length with a transverse partition 11, which is located, preferably, at a point above the horizontal center of the cage, and in this partition is a small central passage 12. The

partition divides the cage into upper and lower chambers, which are connected only by the small passage 12. In the upper part of the upper chamber of the valve-cage is fastened 5 a perforated plate or ring 13, the opening in which establishes communication between the upper chamber of the valve-cage and the fresh-water chamber of the can. A similar perforated plate or ring 14 is fastened 10 in the lower end of the lower chamber of the valve-cage. In the sides of the lower chamber of the valve-cage is provided also a series of slots 15 for the passage of air into the chamber. 15 16 and 17 designate automatic valves, the former being located in the upper chamber and the latter in the lower chamber. The valve 16 is adapted to seat itself upon the partition 11 and to close the passage 12, whereby 20 the water to be frozen contained in the can A is prevented from escaping through the valve-cage. This valve will lift, however, by air or gas pressure from below and allow the air or gas to escape into the water in the can. 25 Should the pressure of the gas or air become less than the pressure of the water from above, the valve will automatically seat itself, closing the passage 12. The upward movement of the valve is limited by the perforated plate 30 13. The valve 17 is made of any material lighter than salt water or brine, and its buoyancy will thus cause it to float on the surface of the brine should the brine rise in the lower chamber 6 of the can and be carried 35 up and seat itself against the under side of the partition 11 of the cage, thereby closing the passage 12 and preventing the brine from getting into the can or, rather, fresh-water chamber of the can. The slots 15 in 40 the valve-cage allow the air or gas to pass into the lower chamber of the cage and to have access to the upper surface of the valve 17, thus preventing the valve from becoming lodged or "stuck" or held in a raised 45 position by the gas or air pressure from below. The air or gas thus having access to all parts of the surface of the valve except that part covering the small aperture 12, the air or gas pressure on any side is balanced 50 by the air or gas pressure from the opposite side, except as to this small part covering the aperture 12. From this description of the valve mechanism it will be seen that the two valves are adapted to be seated automatically 55 by liquid-pressure from above or below, while both valves are adapted to be opened or unseated by gas or air pressure from below—that is to say, the valve 16 will be forced to its seat against the partition 11, and thus 60 close the passage 12 by pressure of the clear or fresh water in the can A when this pressure exceeds the pressure of the air from below—and the valve 17 will rise with the brine should the supply of air or gas cease, and 65 thus close the passage 12, and thus prevent the brine from getting into the fresh water above, and both the valves will be displaced

from their seats when the air or gas pressure is renewed, thus allowing the air or gas to pass into the can. 70

B designates an ordinary air-supply pipe having a series of branches b', one of said branches being preferably provided for each can. To the delivery end of each branch b' is attached a valve-cap 18, which is provided 75 with a port 19, and within this cap is an automatic check-valve 20. The employment of the check-valve 20 prevents the admission of brine into the air or gas pipe; but it is adapted to be unseated by air or gas pressure from 80 below when pressure is on.

As embodied in the construction shown in Figs. 1 and 2 there is no close connection between the can A or attached valve mechanism and the air or gas pipe b'. The air or gas 85 from b', rising by its own buoyancy, is caught in the lower chamber 6 of the can A and displaces the brine, which finds ready outlet from the open bottom of this chamber. As the brine recedes to a point below the valve 90 17 this valve opens, and valve 16 opens by the pressure of the air which now finds access to it and allows air or gas to pass into the can. The weight of the column of brine which presses on the air or gas from below in the 95 chamber 6 of the can A is greater than the weight of the column of equal or smaller height of fresh water within the can, thus insuring that when the can is in place and there is enough air or gas in the chamber 6 to open 100 the valve 17 the pressure on that part of valve 16 which covers the passage 12 will be greater than the fresh-water pressure on the corresponding area opposite, which has until now served to keep the valve seated. 105

In actual practice leaks sometimes occur in the ammonia-pipes, which are immersed in the brine to cool it, thus contaminating the brine, which when it becomes strongly impregnated will give off an odor of ammonia, or the brine may become contaminated in other ways. In order to reduce the contact between the brine and the air that is to pass through the fresh water to a minimum, I use a rubber or other flexible funnel-shaped attachment C. By its elastic neck c' it is attached to the air-pipe b', or it may be attached in any other suitable manner. It has stiffness enough to sustain its own weight and is high enough that when the can A is in place its upper rim c presses lightly against the bottom 5 of the can A and surrounds the valve mechanism. As this funnel C remains attached to the air-pipe b' when the can A is removed it will fill with brine. That this 115 brine may be displaced by air or gas when the can A is again in place I provide a small aperture c² in the lower part of the funnel near the neck, out of which the brine may flow as the air or gas displaces it. It is intended that a small surplus of air or gas shall be admitted through the air-pipe b' in excess of what can find outlet through the small passage 12, thus keeping the chamber 6 of can A filled with 120 125 130

air or gas and the surplus flowing out under the rim 7. The funnel C will thus be kept free from brine after it has been displaced after the can is in place, and the air or gas supply is maintained and the chance of the air that goes through the fresh water in the can becoming contaminated by contact with brine that may have become contaminated is reduced to a minimum.

10 In the embodiment of the invention as shown in Fig. 3 the arrangement is the same as in the foregoing with the following exceptions: A nipple 23 is provided for the cap 18^a of the air-pipe b', and to this nipple is attached a rubber or other flexible tube D. In the upper end of this tube D is inserted a union 22. The tube D is long enough so that when not in use the end to which the union is attached may be held above the top of the 20 brine in the brine-tank. As the can A is about to be placed in the brine the tube D is fastened to the lower valve-chamber of the valve-cage 10 by means of a female thread in the aperture in the ring 14 and male thread 25 on the union 22 or by other suitable means. When the can is removed from the tank to take out the ice or for other cause, the hose is uncoupled by means of the union 22, and the end so uncoupled is kept above the brine. 30 The lower end is kept permanently attached to the air-pipe b'.

No claim is herein made to the specific form of the flexible connector which is embodied in the tube or hose D, (shown by Fig. 3 of 35 this application,) because said subject-matter of invention is disclosed and claimed in a separate application filed by me on April 12, 1902, Serial No. 102,560.

Having thus described my invention, I 40 claim as new and desire to secure by Letters Patent—

1. A freezing-can provided at its bottom with a subchamber and with an air-inlet, an air or gas pipe, and brine-excluding means 45 surrounding the space between the pipe and said air-inlet, said means forming an intermediate chamber having an air or gas outlet in communication with said subchamber of the can, whereby escaping air or gas may exert pressure in said subchamber to displace brine therefrom.

2. A freezing-can provided at its bottom with a double valve having chambers separated by an intermediate partition, and two 55 members which are closed by liquid from above and below respectively, both valve members being opened by air or gas pressure from below.

3. A freezing-can provided at its bottom 60 with a double valve having two members, one of which is buoyant to close by surrounding liquid-pressure, and to be opened by air or gas pressure exerted thereon in one direction, the other valve member being closed by liquid- 65 pressure from the can, and adapted to be opened by air or gas pressure.

4. A freezing-can provided with a valve-

cage and with two valves, one of which is adapted to be closed by liquid-pressure from within the can, and the other of which is buoyant and closed by liquid located externally to the can.

5. A freezing-can provided with a valve-cage having two chambers divided by an intermediate partition in which is formed a passage, a gravity-valve in the upper valve-chamber and a buoyant valve in the lower valve-chamber.

6. A freezing-can provided with a valve-cage divided into two chambers by an intermediate partition, and having slots in the lower portion thereof, and valves confined in said valve-chambers of the valve-cage.

7. The combination with an air or gas pipe, and a removable freezing-can, of a flexible chambered connector attached to the pipe and having its upper open end engaging frictionally with the bottom of said can, said connector being compressible or yieldable under the weight of the can and forming a substantially 90 tight joint with the can solely by said frictional engagement therewith, and a valved air-inlet in the bottom of the can; said air-inlet being surrounded by and in communication with the chamber of the connector, whereby air or gas under pressure from the pipe fills the chamber of the connector and passes through said chamber and the inlet to the can.

8. In combination with an air or gas pipe, and a can having an air-inlet in its bottom, a 100 loose flexible connector attached to said pipe and arranged to fit against the bottom of the can, said connector having a port adapted for the exit of brine.

9. In combination with an air or gas pipe, 105 and a recessed bottom can having an air-inlet and a subchamber, a connection attached to said pipe and operatively fitted to the can, said connector having a port for the exit of brine and for the escape of air or gas into said 110 subchamber of the can.

10. The combination with an air or gas pipe, of a can having a recessed bottom forming a subchamber, a valve-casing attached to said recessed bottom and lying in the subchamber 115 of the can, said valve-casing provided with normally open slots for the circulation of fluid through the same, a movable valve member arranged to play past the slots and having an unrestrained play in the valve-casing within 120 certain limits, and a connector for conveying air or gas from said pipe to the valve-casing.

11. The combination of a freezing-can, an air or gas supply means, and a flexible chambered connector normally attached to said 125 supply means and arranged to discharge air or gas into the freezing-can, said connector being provided with a lateral port or passage at a point between its engagement with the freezing-can and the supply means, whereby 130 brine and air or gas may be discharged from the connector without passing into the can or the supply means.

12. The combination with a freezing-can

and an air-supply pipe, of a chambered connector attached to said pipe and frictionally engaging with the bottom of said can and surrounding the air-inlet thereto, said connector having a brine-vent.

13. The combination with an air or gas pipe and a freezing-can provided with a valve, of a flexible chambered connector having a flexible neck attached to said air-pipe, said connector being of inverted conical form and having its broad upper edge portion engaging loosely with the bottom of said can and surrounding said valve, said connector having a brine-vent.

14. The combination of a freezing-can provided with an air or gas valve, of an air-supply pipe, an inverted conical flexible connector attached to said air-supply pipe and

engaging with the bottom of said can, and a port for the exhaust of gas or liquid from said connector.

15. The combination of a freezing-can having a recessed bottom or chamber, a valve attached to said can and having two members adapted to close by liquid-pressure from above and below but to open by gaseous pressure from below, and a loose flexible connector attached to an air-supply pipe below, and adapted to loosely surround said valve.

In testimony whereof I have signed my name to this specification in the presence of two subscribing witnesses.
